DRIVING MEANS FOR ROLLING DOORS

Nathan Michelman, New York, N. Y.

Application September 12, 1946, Serial No. 696,538

7 Claims. (Cl. 74—407)

1

This invention relates to an improvement in the construction of rolling doors and is more specifically directed to the provision of a new and improved driving and control mechanism for rolling doors adapted to be wound upon and unwound from a drum located at the head of a doorway.

Rolling doors of considerable length and weight, such as are employed in factories, garages, and the like, are generally provided with a driving mechanism operated by an electric motor to facilitate the raising and the lowering of the door. Since, however, such power drive may occasionally break down, a manually operable driving mechanism is also incorporated in the structure. Usually, the two driving mechanisms are entirely independent and are operated through separate gearing means. The resulting structure is therefore complicated and expensive to manufacture.

Therefore I have devised a driving mechanism for operating a rolling door described and claimed in my U. S. Patent No. 2,390,117, granted December 4, 1945, which mechanism comprises power driving means and hand driving means adapted to operate a door through a common set of gears. In the said Patent No. 2,390,117 there are also described and claimed means for automatically shutting off the electric motor at the end of the downward or upward movement of the door, and means for braking the door shaft that are automatically actuated to braking position simultaneously with the shutting off of the electric motor as aforesaid.

The subject matter of this invention is an improvement in the rolling door construction of my aforementioned patent embodying a device for selectively actuating a gearing connected to the shaft of a rolling door from power driving means, or hand driving means, as desired.

In a rolling door, according to this invention, the auxiliary devices for shutting off the electric motor or for braking the door that has been described in my aforementioned patent, can be used advantageously in the same manner and with the same type of mechanical connection as set forth in said patent. However, such auxiliary devices have not been described here because they do not form a part of this invention, though they may be preferably used in connection therewith.

It is the general object of this invention to provide a rolling door structure wherein rotary driven means operatively connected to the rolling door driving shaft may be selectively actuated from a power drive or from a manual drive, as desired.

Another object is to provide a rolling door structure comprising power driving means and manual driving means adapted to operate the door through a common transmission which is selec-

2

tively connectable to either one of said driving means.

A further object is to provide a rolling door structure of the character and properties aforementioned, which structure is particularly simple and economical to manufacture.

A still further object is to provide in a device of a character aforementioned safety means for preventing the power drive from becoming actuated accidentally or through inadvertence while the manual drive is connected.

A still further object is to provide a rolling door structure of the character and properties aforementioned, which embodies an electric motor and a single driven shaft operatively connected to the rolling door shaft, which driven shaft is actuatable directly when the manual drive is connected and becomes the driving shaft.

Other related and ancillary objects of my invention will clearly appear as the description proceeds.

In the drawings:

Fig. 1 is a front view of a device according to the invention, wherein the driving gear which connects the device to the shaft of the rolling door is indicated in phantom lines.

Fig. 2 is a side view of the device of Fig. 1.

Fig. 3 is a longitudinal section of a detail of the device, showing the same with the hand drive disengaged.

Fig. 4 is a section similar to Fig. 3, but showing the hand device engaged.

Referring now in detail to the drawings, 10 indicates generally a frame in which there are mounted the gears 11, shown in phantom lines, which drivingly connect the driven shaft 13 to a shaft 14 of a rolling door. Keyed to the shaft 13, as at 38, there is a pulley 15 which is operatively connected by means of triangular belt 16 to a pulley 17 keyed to the shaft 18 of the rotor of an electric motor 19. The elements aforementioned together constitute the power drive for the rolling door.

On the shaft 13 there is also mounted a sprocket 20, which is free on the shaft and slidable thereon in a longitudinal direction. A helical spring 21 surrounds the shaft 13 and is interposed between the pulley 15 and the sprocket 20 normally to hold the same apart. Attached to the frame 10 there are two brackets 22 upon which there is freely mounted a shaft 23 having a lever 24 keyed thereto at one end thereof. The end of the lever 24 is connected to a tension spring 25 attached to the frame 10 at 26. A chain or other flexible element 27 is also connected to the lever 24 and carries at the lower end thereof a ring 28 adapted to engage a hook 29 secured to the frame 10, but normally at a certain distance below the ring 28. The shaft 23 is centrally bent or cranked up at 30 to form a crank which passes above the shaft 13,

Attached below the bracket 22 there are arms 31 having guides 32 for a chain 33 which engages the sprocket 20.

Normally, the electric motor 19 drives pulley 15 and therefore drives the rolling door shaft 14 through the gearing 11. Since the pulley 15 is fast to the shaft, the sprocket 20 is maintained by the spring 21 as far from said pulley 15 as it will go. In the case illustrated, the sprocket bears against the crank 30. However, a collar or the like could be provided on the shaft to limit the distance of the sprocket from the pulley 15 and stop the sprocket short of the crank 30. At any rate, there is no driving connection between sprocket 20 and shaft 13, or sprocket 20 and pulley 15. Should the motor stop because of power failure or any other reason, an operator may grasp the chain 27, pull it downwardly and engage the ring 28 into the hook 29 which will therefore hold the chain in a lowered position. This latter will hold the lever in a downswing position. Means equivalent to, but different from the chain-ring-hook arrangement described could be employed to hold said lever in its downswing position. During the downward swing of the lever 24, the following motions take place: The shaft 23 rotates clockwise as viewed in Fig. 2. The crank 30 swings downwardly, bears against the sprocket 20 and urges the same toward pulley 15 compressing the spring 21. The sprocket 20 has formed in its hub on the end thereof facing the pulley 15 a projection or tooth 35 which can be provided by cutting down the hub except for a small portion thereof bordered by two radii. The pulley 15 has on its hub a corresponding projection or tooth 34 facing the sprocket 20. When the sprocket is moved to the right the cut-down portion of its hub will contact the tooth 34, while the cut-down portion of the hub of the pulley 15 will contact the tooth 35. The two teeth generally will not be in contact, but upon a relative rotation of less than one revolution of the sprocket 20 and pulley 15 in either direction said teeth will contact each other and the whole assembly will remain in such a relationship as shown in Fig. 4, as long as the ring 28 stays engaged with the hook 29. Concurrently the arm 24 or a projection thereof or a means operatively associated thereto bears on the button 36 of a switch 37, which interrupts the circuit of the electric motor 19, and therefore assures that the said motor will not be started accidentally or by inadvertence if power is restored or whatever failure caused the stopping of the motor is repaired. The pulley 17 remains engaged through the belt 16 with the pulley 15. If now the chain 33 is manually actuated in one or the other direction, the teeth 34 and 35 will come into contact, if they are not already, and thereafter the sprocket 20 will actuate the pulley 15 and therefore the rolling door and at the same time will cause the pulley 17, the shaft 18 and the rotor of the electric motor 19 to rotate idly. A roller or roller bearing or other device adapted to minimize friction could be attached to the crank 30 or suitably interposed between said crank and the sprocket 20. Also a suitably shaped eccentric member fast to the shaft 23 could be substituted for the crank 30, and the switch 37 could be actuated concurrently to the engagement of the hand drive by means operatively connected to the sprocket 20 rather than to the shaft 23 as in the case illustrated.

When it is desired to re-engage the power drive, the ring 18 is withdrawn from the hook 29. The

spring 25 pulls the lever 24 back to its operative position, the switch 37 is released, the spring 21 disengages the sprocket 20, and the whole device returns to the position illustrated in Figs. 2 and 3.

As mentioned at the beginning of this specification, auxiliary mechanisms of the type described in my Patent 2,390,117 could be embodied in the driving device herein described in the same manner in which they are embodied in the driving device described in the said patent. For this reason it has been thought unnecessary to show or describe herein such auxiliary mechanisms. Likewise, the gearing 11 which is of the same type as the gearing shown in the same Patent 2,390,117 could be replaced by another gearing or a driving or a reduction device. Substantially this invention is only concerned with the driving connection between the motor 19 on the one hand and the chain 33 on the other and the driven shaft 13.

While I have described a preferred embodiment of my invention, it is understood that many changes and modifications could be made therein without departing from the spirit of the invention or exceeding the scope of the claims.

I claim:

1. In a driving mechanism for rolling doors, a driven shaft, transmission means for operatively connecting said driven shaft to a rolling door shaft, a pulley keyed to said driven shaft, an electric motor driving said pulley, a driving wheel free on said driven shaft and displaceable thereon between an engaged position wherein it is drivingly coupled to said pulley and a disengaged position wherein it is not so coupled, means for manually rotating said wheel, resilient means for normally maintaining said wheel in its disengaged position, hand-operated means for overcoming said resilient means to actuate said wheel to its engaged position whereby to permit manual operation of the mechanism, means for locking said hand-operated means to maintain said wheel in its engaged position, switch means actuatable to render said electric motor inoperative, and means operatively associated with said hand-operated means for maintaining said switch means actuated while said wheel is in its engaged position.

2. In a driving mechanism for rolling doors, a driven shaft, transmission means for operatively connecting said driven shaft to a rolling door shaft, a pulley keyed to said driven shaft, an electric motor driving said pulley, a driving wheel free on said driven shaft and displaceable thereon between an engaged position wherein it is drivingly coupled to said pulley and a disengaged position wherein it is not so coupled, means for manually rotating said wheel, resilient means for normally maintaining said wheel in its disengaged position, a control shaft substantially perpendicular to said driven shaft, hand-operated means for rotating said control shaft to an angularly displaced position, an eccentric member fast to said control shaft adjacent said wheel, said member when said control shaft is so rotated engaging said wheel and displacing the same to its engaged position whereby to permit manual operation of the mechanism, switch means actuatable to render said electric motor inoperative, and means operatively associated with said hand-operated means for maintaining said switch means actuated while said shaft is in an angularly displaced position.

3. In a driving mechanism for rolling doors, a driven shaft, transmission means for opera-

tively connecting said driven shaft to a rolling door shaft, a pulley keyed to said driven shaft, an electric motor driving said pulley, a driving wheel free on said driven shaft and displaceable thereon between an engaged position wherein it is drivingly coupled to said pulley and a disengaged position wherein it is not so coupled, means for manually rotating said wheel, resilient means for normally maintaining said wheel in its disengaged position, a control shaft substantially perpendicular to said driven shaft and having a cranked portion adjacent said wheel, resilient means for urging said control shaft to a neutral position, hand-operated means for rotating said control shaft to an operative position thereby causing said cranked portion thereof to engage said wheel and force the latter to its engaged position to permit manual operation of the mechanism, means for locking said shaft in its operative position, switch means actuatable to render said electric motor inoperative, and means operatively associated with said hand-operated means for maintaining said switch means actuated while said control shaft is in its operative position.

4. In a driving mechanism for rolling doors, a driven shaft, transmission means for operatively connecting said driven shaft to a rolling door shaft, a pulley keyed to said driven shaft, an electric motor driving said pulley, a driving wheel free on said driven shaft and displaceable thereon with respect to said pulley between a juxtaposed and a spaced position, clutch means for drivingly coupling said wheel to said pulley when said wheel is in said juxtaposed position, means for manually rotating said wheel, resilient means for urging said wheel to said spaced position, hand-operated means for actuating said wheel to said juxtaposed position, whereby to engage said clutch means and to permit manual operation of the mechanism, means for locking said hand-operated means to maintain said clutch means in engagement, switch means actuatable to render said electric motor inoperative, and means operatively associated with said hand-operated means for maintaining said switch means actuated while said clutch means are in engagement.

5. In a driving mechanism for rolling doors, a driven shaft, transmission means for operatively connecting said driven shaft to a rolling door shaft, a pulley keyed to said driven shaft, an electric motor driving said pulley, a driving wheel free on said driven shaft, at least one projection on the hub of said pulley, at least another projection on the hub of said wheel, resilient means for normally holding said pulley and wheel in spaced relationship, hand-operated means for displacing said wheel towards said pulley to a position wherein said projections drivingly couple said wheel to said pulley, whereby the mechanism may be manually operated, means for locking said hand-operated means to maintain said projections in mutual engagement, switch means actuatable to render said electric motor inoperative, and means operatively associated with said hand-operated means for maintaining said switch means actuated while said projections are in mutual engagement.

6. In a driving mechanism for rolling doors,

a driven shaft, transmission means for operatively connecting said driven shaft to a rolling door shaft, a pulley keyed to said driven shaft, an electric motor driving said pulley, a driving wheel free on said driven shaft and displaceable thereon between an engaged position wherein it is drivingly coupled to said pulley and a disengaged position wherein it is not so coupled, means for manually rotating said wheel, resilient means for normally maintaining said wheel in its disengaged position, a control shaft substantially perpendicular to said driven shaft, an eccentric member fast to said control shaft adjacent said wheel, a lever fast to said control shaft, a resilient member attached to said lever for normally maintaining said control shaft in a neutral position, means for manually swinging said lever angularly to displace said control shaft, whereby to cause said eccentric member to engage said wheel and displace the same to its engaged position, means for releasably locking said lever in its swung position, switch means actuatable to render said electric motor inoperative, said lever when in its swung position maintaining said switch means so actuated.

7. In a driving mechanism for rolling doors, a frame, a driven shaft, transmission means for operatively connecting said driven shaft to a rolling door shaft, a pulley keyed to said driven shaft, an electric motor driving said pulley, a sprocket free on said driven shaft and axially slidable thereon, a chain for manually rotating said sprocket, at least one projection on the hub of said pulley facing said sprocket, at least one projection on the hub of said sprocket facing said pulley, spring means for normally maintaining said pulley and sprocket in spaced relationship thereby preventing engagement of said projections, a control shaft substantially perpendicular to said driven shaft, a cranked portion on said control shaft adjacent said sprocket, a lever fast to said control shaft, a spring attached to said lever and to said frame and normally maintaining said control shaft in a position wherein said cranked portion thereof is substantially perpendicular to said driven shaft, a flexible element attached to said lever for manually swinging this latter and therefore angularly displacing said control shaft whereby to cause said cranked portion of this latter to actuate said sprocket axially and force it to a position adjacent said pulley wherein said projections drivingly couple said sprocket to said pulley, hook means for releasably locking said lever in its swung position to maintain said driving coupling, and a switch actuatable to render said electric motor inoperative, said lever when in its swung position actuating said switch.
